CLAIM

The ornamental design for a combined secure digital
memory and subscriber identity module, as shown and
described.

DESCRIPTION

FIG. 1 is a front perspective exploded view of the combined
secure digital memory and subscriber identity module.

FIG. 2 is a rear perspective exploded view thereof;

FIG. 3 is a plan front exploded view thereof;

FIG. 4 is a plan rear exploded view thereof;

FIG. 5 is a right side exploded view thereof;

FIG. 6 is a left side exploded view thereof;

FIG. 7 is a top exploded view thereof;

FIG. 8 is a bottom exploded view thereof;

FIG. 9 is a front perspective view of the combined secure
digital memory and subscriber identity module; and,

FIG. 10 is a rear perspective view thereof.
